HOUSING FOR AN AQUARIUM HEATER

Allan H. Willinger, 56 Gail Drive, New Rochelle, N.Y.

Filed Oct. 29, 1959, Ser. No. 58,121

Term of patent 14 years

(Cl. D81—2)

FIG.1

FIG.2

FIG.3

FIG.4

FIG.5

FIG.6

Figure 1 is a front elevational view of a housing for an aquarium heater, showing my new design;

Figure 2 is a side elevational view thereof;

Figure 3 is a rear elevational view thereof;

Figure 4 is a top view thereof;

Figure 5 is a top plan view thereof with the cover removed; and

Figure 6 is a side elevational view thereof with the cover removed.

I claim:

The ornamental design for a housing for an aquarium heater, substantially as shown.
